UNITED STATES PATENT OFFICE.

CLARA B. SNYDER, OF FOSTORIA, OHIO, ASSIGNOR TO AMERICAN FOG SIGNAL COMPANY, OF PITTSBURGH, PENNSYLVANIA.

RAILWAY-TORPEDO.

1,102,966.

Specification of Letters Patent. Patented July 7, 1914.

Application filed June 17, 1910. Serial No. 567,454.

To all whom it may concern:

Be it known that I, CLARA B. SNYDER, a citizen of the United States, residing at Fostoria, in the county of Hancock and State of Ohio, have invented certain new and useful Improvements in Railway-Torpedoes, of which the following is a specification.

This invention relates to improvements in railway signal torpedoes the object of which 10 is to provide a torpedo composed of a double fiber case of an improved construction, which will be pointed out hereinafter.

In the accompanying drawings Figure 1 is an inverted plan view of my improved 15 torpedo. Fig. 2 is a top plan view thereof. Fig. 3 is a transverse sectional view taken at right angles to the rail engaging strap. Fig. 4 is a sectional view taken longitudinal 20 the rail engaging strap.

My improved torpedo comprises an inner explosive containing case 1 which consists of telescoped cup shaped members in which the explosive compound is placed as shown 25 in Figs. 3 and 4, and an outer inclosing case 2.

The outer inclosing case 2 is made from 30 a section of a tube. Both cases are composed of a fibrous material, such for instance as paper. After the explosive compound is placed within the inner case 1 and the two parts thereof arranged in telescope relation, the case is externally waterproofed with any suitable waterproof compound. This explosive containing case is then placed within the outer case 2 by passing it through one of 35 its open ends, and the ends of the tubular outer case 2 are doubled over as shown in Fig. 4 and fastened by suitable staples 5. Both ends of the tube may be left open at the time the inner case is placed therein, or

one end of the tube closed and the inner case passed through the open end of the tube, after which that end of the tube is closed in the manner described. The rail 40 engaging strap 4 of lead or other pliable 45 metal is secured to the outer side of the tubular case 2, preferably by means of two of the staples 5 which also serve to secure the doubled ends of the tube 2.

By reference to the drawings it will be 50 observed that the completed torpedo is of rectangular shape in plan, and by reason of the inner case 1 being of less area than the outer case, the outer tubular case has flexible ends which will be caught and clamped by 55 the wheels of the locomotive before the inner

filled case is reached by the wheel. These projecting ends being unfilled or vacant, the locomotive wheels do not strike a solid portion of the torpedo, and this avoids the well known tendency of torpedoes with solid abrupt walls to be pushed, slid, or "popped" 60 from under the wheel and thrown from the track without being exploded.

If desired, the completed torpedo may be 65 immersed in a waterproof compound.

While the drawings show the lead attaching strap above the torpedo, it will be understood that the torpedo can be reversed on the rail with the lead strap resting flat thereon without departing from the invention. 70

Having thus described my invention, what I claim and desire to secure by Letters Patent is:

1. A railway signal torpedo comprising 75 an inner case and an outer inclosing case, the ends of the outer case projecting considerably beyond the inner case, and a rail-engaging means attached to the said extending ends of the outer case. 80

2. A railway signal torpedo comprising 85 an inner case composed of fibrous material, an outer inclosing case composed of flexible fibrous material, the ends of the outer case projecting considerably beyond the inner case, and a rail-engaging means extending across the extended ends of the outer case, and means for closing the extended end of the outer case, and simultaneously securing the rail-engaging means 90 thereto.

3. A railway signal torpedo comprising 95 an inner case, composed of fibrous material, an outer inclosing case composed of flexible fibrous material, the ends of the outer case projecting considerably beyond the inner case, a rail-engaging strap extending across the projecting ends of the outer case, and means passing through the projecting ends 100 of the outer case and through the rail-engaging strap, whereby the extended end of the outer case is closed, and the rail-engaging strap simultaneously secured thereto.

4. A railway signal torpedo comprising 105 an inner case composed of fibrous material, an explosive compound within the said inner case, an outer inclosing case composed of flexible fibrous material, the ends of the outer case projecting considerably beyond 110

the inner case, and terminating in abutting edges, the said abutting edges doubled, a rail-engaging strap passing across said doubled ends of the outer case, and means passing through the doubled edges of the outer case, and the rail-engaging strap, whereby the doubled end of the outer case is securely closed and the rail-engaging strap simultaneously attached thereto.

10 5. A railway torpedo, comprising an inclosing case, an explosive mixture within

the inclosing case, the ends of said case projecting considerably beyond the explosive mixture and a rail-engaging means attached to the said extending ends of the case.

15.

The foregoing specification signed at Fostoria, Ohio, this 9th day of June, 1910.

CLARA B. SNYDER.

In presence of—

E. E. MILLER,
Geo. H. SPARKS.
